COUNTER TOP COOKING UNIT

Emery J. Poracki, South Gate, Calif., assignor to O'Keefe & Merritt Company, Los Angeles, Calif., a corporation of California

Filed Jan. 13, 1958, Ser. No. 49,237

Term of patent 14 years

(Cl. D81—25)

Fig. 1 is a top perspective view of a counter top cooking unit showing my new design taken from the front;

Fig. 2 is a top perspective view thereof taken from the rear and opposite side;

Fig. 3 is a top plan view of the unit; and

Fig. 4 is a fragmentary sectional view taken on the line 4—4 of Fig. 3 in the direction of the arrows.

I claim:

The ornamental design for a counter top cooking unit, as shown.
